UNITED STATES PATENT OFFICE.

THOMAS B. WHITLEDGE, GEORGE W. KENNER, AND MICHAEL RUECKERT,
OF ST. MARY'S, MISSOURI.

TOBACCO-PIPE.

SPECIFICATION forming part of Letters Patent No. 388,235, dated August 21, 1883.

Application filed September 13, 1887. Serial No. 249,567. (No model.)

To all whom it may concern:

Be it known that we, THOMAS B. WHITLEDGE, GEORGE W. KENNER, and MICHAEL RUECKERT, of St. Mary's, in the county of Ste. 5 Genevieve and State of Missouri, have invented new and Improved Tobacco-Pipes, of which the following is a full, clear, and exact description.

The object of the present invention is to provide for the bowl of a tobacco-pipe means for preventing the tobacco therein from falling therefrom, for pressing the tobacco more closely and compactly in the bowl, or for loosening the same if pressed too closely, and for 15 scraping and cleaning the bottom of the bowl. The invention consists in combining with an apertured cap various parts operating in relation to each other, the cap, and the interior of the pipe-bowl, all substantially as hereinabove described, and pointed out in the claims.

Reference is to be had to the accompanying drawings, forming a part of this specification, in which similar letters of reference indicate corresponding parts in all the figures.

Figure 1 is a central section through the pipe-bowl, with its cap or lid shown as closed, and with the tobacco-presser and bowl-cleaner as in their uppermost position. Fig. 2 is a sectional view similar to Fig. 1, but showing the 25 tobacco-presser and bowl-cleaner as pressed and held in their lowermost position. Fig. 3 is a plan view of the pipe with its lid or cap shown as swung open, parts being broken away to better disclose the construction, and 30 Figs. 4 and 5 are views in detail, to be herein-after referred to.

In the drawings, A represents a tobacco-pipe, of which B is the bowl, and C the stem, having the usual smoke drawing passage, a, 40 entering the bowl at b.

D is a ring-plate having a flange, d, fitting and lying over the upper outer edge or periphery of the bowl, and to this ring-plate D, at a point near to but inside of the line of the bowl-45 stem, is hinged a cap or lid, E, (here shown as of dome or hemispherical shape and as provided with apertures or air-holes f.) This lid at its base has a web, g, passing from side to side thereof and across its axial line. An axial spindle or pusher-rod, G, passes through 50 bearings h h, formed by holes in the top of the

cap and at the center of the web g, which pusher-rod is provided at its upper end with a knob or button, j, and carries at its lower end a disk, H, constituting the tobacco pusher or 55 presser. The disk H is provided with perforations k k, and between the upper side of the web g and a collar, l, on the stem, inside of the cap, is disposed a spiral spring, m.

Rigidly secured to and projecting downwardly from a point near the rim of the pusher-disk is a bowl-cleaner arm, J, which is curved at its free end to fit the bottom of the bowl. The stem carrying the pusher-disk and cleaner-arm fitting loosely in the bearings h 65 h, permits a free rotation of said stem, and consequently of the disk H and arm J.

The pusher-stem G is provided with a thin radial projection, i, and in the web g is formed a slot, i², through which, when the stem is 70 pressed downwardly, carrying therewith the pusher-disk and cleaner-arm into the lower portion of the bowl and partially rotated, its shoulder i passes freely, and when the pusher-stem is forced downwardly, carrying therewith the pusher-disk and cleaner-arm into the lower portion 75 of the bowl and partially rotated, its shoulder i engages the under side of the web g, and the stem is prevented from being forced upwardly, and this disposition of the pusher-stem within the bowl, with its projecting knob j close to the top of the cap, as illustrated in Fig. 2, is 80 desirable when the pipe is to be carried in the pocket.

The lid E has a hooked projection, n, projecting downwardly therefrom, which, when the lid is closed, passes through a slot, p, in 85 the top of ring D and engages an arc-shaped bolt, q, having an outward projection, r, passing through a slot, s, in the flange d of plate D, said bolt q being adapted, through its projection r, to be moved backward and forward, 90 in the one instance securing the lid closed upon the bowl, and in the other releasing it to be opened. The knob or button j and pusher-disk H are attached to the pusher-stem and the bowl-cleaning arm J to the disk H by having screw-threads t formed thereon, so that by unscrewing said parts they may be removed and set aside, thereby leaving the bowl simply covered by a hinged lid, as at all times it may not be desirable to employ the tobacco-pusher 95 and bowl-scraper in connection with the pipe.

It will be seen that the present invention

affords to the pipe, and as a part thereof, a ready means of tamping the tobacco therein, loosening the same if too compactly pressed, of reaching the interior walls and bottom of the pipe, and of preventing the tobacco sparks or ashes within the bowl from falling therefrom, and all without in any way interfering with the free operation of the pipe.

Having thus described our invention, what we claim as new, and desire to secure by Letters Patent, is—

1. The combination, with an apertured pipe-cap, of a pusher-rod, a presser-disk carried by said rod, a bowl-cleaning arm carried by said disk, and a retracting spring, arranged for operation substantially as shown and described.

2. The combination, with a ring adapted to fit a pipe-bowl, of an apertured dome-shaped cap hinged thereto, a presser-rod held to slide in said cap, an apertured presser-disk carried by said rod, a bowl-cleaning arm carried by said disk, a retracting spring on said rod, and a spring catch on the cap and ring, substantially as and for the purpose described.

3. The combination, with a cap hinged to a ring adapted to fit a pipe-bowl and provided with a web, *g*, said cap and web being apertured to form bearings *h*, of a rod, *G*, provided with a shoulder, *l*, a disk, *H*, a bowl-cleaning arm, *J*, and a spring, *m*, substantially as and for the purpose described.

4. The combination, with a cap hinged to a ring adapted to fit a pipe-bowl and provided with a web, *g*, said cap and web being apertured to form bearings *h*, and said web having slot *i*, of a rod, *G*, provided with shoulders *l*

and *i*, a disk, *H*, a bowl-cleaning arm, *J*, and a spring, *m*, substantially as and for the purpose described.

5. The combination, with a pipe-bowl, of an opening and closing apertured cover or lid provided with a pusher-stem having suitable bearings in said lid, and having secured thereto a bowl-cleaning arm, *J*, substantially as described.

6. The combination, with the pipe-bowl, of an opening and closing apertured cover or lid, a sliding pusher-stem having bearings in said cover or lid, a spring for forcing said stem upward, and a bowl-cleaning arm connected to the pusher-stem, substantially as described.

7. The combination, with the pipe-bowl, of an opening and closing apertured cover or lid provided with a pusher stem having suitable bearings in said lid for movement with and against a spring pressure, and having secured thereto a pusher-disk, *H*, and a bowl-cleaning arm, *J*, substantially as and for the purpose described.

8. The combination, with the pipe-bowl, of an opening and closing apertured lid or cover of dome shape provided with a pusher-stem having bearings *h* in said lid, provided with a pusher-disk, *H*, a bowl-cleaning arm, and a spiral spring, *m*, arranged between a shoulder, *l*, on the pusher stem and the lower bearing, *h*, substantially as and for the purpose described.
